Attorneys.

UNITED STATES PATENT OFFICE.

ISAAC ANDREWS, OF SPARTANBURG, SOUTH CAROLINA.

LOOM REED.

Application filed April 7, 1927. Serial No. 181,833.

This invention has reference to loom-reeds, the primary object of the invention being to provide novel means for mounting the dents of a reed whereby the reeds will 5 be instantaneously returned to their initial positions upon the removal of a drawing-in hook, knot in the thread or other element causing the dents to be spread.

Another object of the invention is to provide 10 means connected with the extended ends of the dents for returning the dents to their initial positions should they be bent laterally.

A still further object of the invention is 15 to improve generally the construction shown in my copending application, Serial Number 149,719.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawing:

Figure 1 is a vertical sectional view 30 through a loom-reed constructed in accordance with the invention.

Figure 2 is a fragmental elevational view 35 thereof, a portion of one of the ribs being broken away.

Referring to the drawing in detail, the reference character 5 indicates the dents of the loom-reed, at both ends of which and arranged on opposite sides thereof, are the 40 ribs 6 that support the ends of the dents and provide means whereby the dents may be supported in a lathe.

The dents are arranged in suitable spaced 45 relation with each other and held in such spaced relation by means of the cotton binding member 7, which is wrapped around the ribs as shown by the drawing, portions thereof lying between the dents.

The ends of the dents extend beyond the 50 ribs 6, and are indicated by the reference character 8, which ends are secured by means of the rubber strips 9, the rubber being

flexible and vulcanized around the extended ends 8 of the dents, and secured thereto, as clearly shown by Figure 1. This rubber 55 also extends laterally and acts as a binding medium for binding the cotton 7 in position.

It might be further stated that while the dents are held between the ribs 6, at the ends of the dents, the dents are free to move 60 between the ribs, allowing the dents to be separated as shown in dotted lines in Figure 2.

From the foregoing it will be seen that due to this construction, when the dents are 65 moved laterally or spread apart as by a drawing-in hook, being positioned therebetween or by a knot in the thread passing between the dents, instantaneously with the removal of the hook or knot, the dents 70 will automatically return to their initial positions.

It will be seen that as the dents are moved laterally as indicated in dotted lines, the rubber strip 9 will be drawn downwardly, and 75 since this rubber strip is secured to the extended ends 8 of the dents, the rubber strip will act to exert a pull on the dents, returning them to their initial positions.

As illustrated by Figure 2, the dotted line 80 A indicates the action of the rubber strip 9 as the dents are spread.

I claim:

1. A loom-reed including spaced dents, supports connecting the dents adjacent to 85 the ends of the dents, the ends of the dents extending beyond the supports said dents adapted to move within the supports and flexible means cooperating with the extended ends of the dents for moving the dents 90 within the supports.

2. A loom-reed including supports, dents mounted in the supports and adapted to move therein, the ends of the dents extending beyond the supports, elastic means connected 95 with the extended ends of the dents, and said elastic means adapted to return the dents to their initial positions when the dents are spread laterally.

3. A loom-reed including supports, dents connected with the supports and adapted to move therein, the extremities of the dents extending beyond the supports, flexible rubber strips vulcanized to the extended ends of

the dents, and said rubber strips adapted to move the dents and return the dents to their normal positions after they have been spread apart.

5. A loom reed including spaced dents, supports connecting the dents adjacent to the ends of the dents, the ends of the dents extending beyond the supports, said dents

adapted to move within the supports and the extending ends of the dents embedded in ¹⁰ elastic material.

In testimony that I claim the foregoing as my own, I have hereto affixed my signature.

ISAAC ANDREWS.
